MICA SPLITTING APPARATUS

Moses D. Heyman, Woodmere, N. Y.

Application May 26, 1950, Serial No. 164,333

6 Claims. (Cl. 125—24)

1

This invention relates to apparatus for splitting pieces of mica, the same being more particularly employed in the production of integrated mica as disclosed in my Patent Numbers 2,405,576 and 2,490,129. The present apparatus is an improvement of the mica splitting means shown in said patents.

An object of the present invention is to provide novel mica splitting apparatus wherein the force of splitting jets is so applied that improved circulation of the mica pieces that are being split is obtained, such improved circulation affording a more frequent presentation of the mica pieces to the action of the jets with resultant improved splitting efficiency.

Another object of the invention is to provide a multichamber disintegrator in which the initial or lowermost chamber more efficiently circulates and splits mica pieces placed therein.

Another object of the invention is to provide means that creates back pressure in the chambers of the disintegrator during operation thereof, by retarding flow from each chamber to the one next above, and to provide novel means receptive of and storing liquid displaced from the disintegrator chambers under such conditions of pressure, said stored liquid being utilized, when the operation of the disintegrator has been stopped, to float mica splittings upwardly from one chamber to the other.

A further object of the invention is to provide mica splitting apparatus designed to afford a visual check of the circulation in the chambers of the disintegrator and particularly the lowermost chamber, so that the rate of feed of mica pieces thereinto can be determined to obviate clogging and for maintaining the operation at maximum efficiency.

A further object of the invention is to provide apparatus of improved and flexible construction, particularly in the improved design of the jet means, whereby the same can be easily and quickly replaced when worn or otherwise rendered inefficient.

A still further object of the invention is to provide a novel and improved method for splitting mica in which the splitting operation is alternately started and stopped to, alternately increase and relieve the pressure in the splitting chambers to, thereby, intermittently float the lighter splittings upwardly through the successive chambers.

Other objects of the invention are to provide novel combinations and arrangements of parts and novel details of construction, which will more fully appear in the course of the following

2

description. The accompanying drawings merely show and the description merely describes a preferred embodiment of the present invention, the same being given by way of illustration or example only.

In the drawings:

Fig. 1 is a vertical sectional view of mica splitting apparatus according to the present invention.

Fig. 2 is a front elevational view thereof as seen in the direction of arrow 2 of Fig. 1.

Fig. 3 is an enlarged sectional view as taken on line 3—3 of Fig. 1.

The present mica splitting apparatus comprises, generally, a disintegrator 5, a support 6 therefor, liquid-receiving and mica-piece feeding means 7 connected to the disintegrator at the lower end thereof, and means 8 to feed liquid from an inlet 9 to the disintegrator to split mica pieces therein.

The disintegrator 5 comprises an elongated body casting 10 in which is provided a series of chambers 11, 12, 13, 14, 15 and 16 arranged from the lower end of said casting upward. The lowermost chamber 11 is preferably larger than those above and the latter may be successively smaller or of the same size, as desired. As shown, chamber 12 is somewhat larger and chamber 16 somewhat smaller than chambers 13, 14 and 15. Said chambers are formed as through openings extending from front to back of casting 10. The chambers may be of oval form, as shown, or of the circular form of chamber 16, although the oval form is desired for at least the lower chambers of the series.

Between adjacent chambers and serving to connect them, there are provided throats 17, 18, 19, 20 and 21 from the bottom upward, throat 17 being widest and the others being successively narrower, substantially as shown.

Against the back face of casting 10, there is placed a back plate 22 to close the chambers at the back, a suitable gasket 23 being interposed to seal against leakage from the chambers. At the front of casting 10, there is placed a transparent face plate 24 that is removably held in place by a set of clamps 25, a gasket 26 serving to seal between plate 24 and the front face of casting 10. Thus, the chambers are closed front and back and are in communication with each other only through the throats above described.

The disintegrator is provided with an outlet 27 that consists of a short tube carried by face plate 24. Said outlet is aligned with uppermost chamber 16 and receives flow therefrom. The inlets

for the disintegrator will be described in connection with means 7 and 8. A drain is provided for emptying the disintegrator, when such is desired, and is shown as a pipe 28 connected to the lower portion of chamber 11.

It will be noted that the disintegrator is shown as disposed at a forward angle. In practice, it has been found that such forward tilting results in improved operation, although a vertical position has given results only slightly less satisfactory than those obtained by an angular position.

The disintegrator is supported in its tilted position by a support structure 6 secured to lateral brackets 29 provided on body casting 10.

The mica-piece feeding means 7 comprises a substantially vertical funnel 30 that has a sloping lower end 31 which, through a suitable opening in back plate 22 of the disintegrator, enters into lowermost chamber 11. It will be noted that the top of the funnel is considerably higher than the upper end of the disintegrator and that the liquid capacity of the same is considerably greater than that of the disintegrator chambers. Said funnel is advantageously made of transparent plastic so that the liquid levels therein are visible from the outside. A flange 32, secured by suitable bolts, serves to mount the funnel on the back wall 22 of the disintegrator.

The liquid-feeding means 8 comprises a series of tubes 33, 34, 35, 36 and 37 extending transversely through the lips, on one side, that define the throats 17 to 21. Each tube, as suggested in Fig. 1, is provided with a line of perforations 38 that is so positioned that liquid discharged therefrom will be directed tangentially to impinge on the walls of the respective chambers immediately beneath the lips 38 opposite to the lips through which the perforated tubes extend. The perforations are so spaced that jets of liquid from each tube constitute effective curtains or barriers to flow upwardly from one chamber to another. The action of the jets, as more clearly shown at 39 of Fig. 3, will be more fully described hereinafter.

In addition to tube 33, chamber 11 is provided with two tubes 40 extending across opposite sides of said chamber. Said tubes 40 each have a line of perforations 41 so positioned that the resultant jets 42 are also directed to be tangential to the wall of chamber 11, the three jets 39, 42, 42, being mutually arranged to drive or swirl liquid in said chamber in one direction, in this case, clock-wise as viewed through face plate 24.

Tubes 40 are fed directly from inlet 9 in which is provided a T fitting 43, pipes 44, provided with suitable connection unions, connecting tubes 40 with T fitting 43.

A manifold 45 receives flow from the T fitting 43 through a connection 46, and the chamber 47 of said manifold is connected by pipes 48, 49, 50, 51 and 52 to the respective tubes 33 to 37. On the inlet side of the T fitting 43, there is provided a flow control valve 53, and a pressure gauge 54 is provided for manifold chamber 47 to show the pressure of liquid therein so that valve 53 may be set accordingly.

Because of the high pressure of the liquid, perforations 38 and 41, in time, enlarge with a resultant lowering of the jet velocity and pressure. When this occurs, the tubes 33 to 37 and 70 the tubes 40 can be readily replaced by breaking the unions connecting them to their respective feed pipes and withdrawing them from their seats in housing 10. Also, these tubes can be rotated in their seats to adjust the angle of the

jets with relation to the throats thereabove and to achieve the desired tangency with the wall of the chamber into which the jets are directed.

Operation

5 The apparatus is filled with liquid through funnel 30 and will accept liquid only to the level indicated at 55 without overflowing through outlet 27. Then pieces of mica are dropped into the funnel and the same will fall to the bottom of chamber 11, said pieces being of such size and weight as to sink to the bottom. Valve 53 is then opened so that additional liquid enters the chambers in the form of high pressure jets 39 and 42. In practice, the force of these jets is in the nature of 500 lbs. per square inch. Therefore, the jets have considerable power to split the mica pieces at such time that any edge of said pieces is impinged by the jets.

With particular reference to Fig. 3, it will be seen that jet 39, aided by jets 42, imparts a swirling motion to the liquid in chamber 11 in the direction of the curved arrows, the mica pieces in the liquid being swirled and rotated accordingly. Centrifugal force throws these pieces outwardly and, in following the course of least resistance, they assume a position generally tangential to the peripheral face of the chamber. Disposed in this manner, the mica pieces move in a path whereby they are substantially parallel to the jets as they move thereby. Accordingly, the jets 39 and 42 each have many opportunities to strike against the trailing edges of the mica pieces and to split the same, as suggested in Fig. 3. It will be understood that the velocity of the jets is considerably greater than the speed of rotation of the mass of water or other liquid and the pieces of mica therein so that said high velocity of the jets is highly effective as a splitting force.

40 In practice, the splitting action is carried out only for a matter of some five seconds and, during that short period, some 350 cu. in. of liquid is added to the liquid already in the apparatus. Since the velocity of jet 39 is of such magnitude as to, in effect, serve as a gate or barrier to upward flow from the chamber, considerable pressure is created in the chamber resulting in flow from the chamber into the funnel against the relatively low head of liquid in said funnel. Thus, the head in the funnel is increased during jet operation to the higher level 56 and considerably above the level of outlet 27.

55 After the short period of application of jet pressure, valve 53 is closed to stop further flow. Since the higher level 56 naturally seeks the lower level in the disintegrator, the liquid in the funnel, at low pressure, flows back into chamber 11 causing a lifting of the quiescent liquid in the chamber. Thus, thinly split and buoyant mica flakes in said liquid will be lifted from chamber 11, past throat 17, into chamber 12. This quiescent period is also relatively short, a matter of some five seconds.

60 The foregoing constitutes one cycle of operation and is repeated to obtain intermittent discharge of mica-laden liquid from the disintegrator. For each cycle of operation, the mica split in the lowermost chamber 11 provides smaller pieces and flakes that float into chamber 12. In the same manner, chamber 12 carries out its splitting operation, simultaneously, and provides still smaller splittings that float upward into chamber 13. Consequently, the mica flakes that eventually float into chamber 16 are quite thin and exit from outlet 27.

The perforations 33 are so closely spaced that the barriers formed by jets 39 are highly efficient to prevent upward flow in the disintegrator and, in practice, no liquid is observed flowing out of outlet 27 during the operation of the jets, such flow being had only during the quiescent period of the cycle of operation. From time to time, additional mica pieces are deposited into the funnel and, by observing the rotation of the pieces while the jets are on, the rate of feed of said pieces can be determined so as to obtain high output without clogging of the apparatus.

The product obtained at outlet 27 may be used for producing sheets of integrated mica or the same may be screened so that the larger particles and thicker flakes may be sent through a smaller but similar splitting apparatus for further reduction in size or thickness.

Of course, the number of splitting chambers may vary according to the gauge of splittings desired as also may be the number of splitting devices that are employed in series.

A variation entails making the back plate 22 transparent instead of opaque. The action in the chambers of the disintegrator can be better observed by lighting from behind when both back and front plates are transparent.

While I have illustrated and described what I now regard as the preferred embodiment of my invention, the construction is, of course, subject to modification without departing from the spirit and scope of my invention. I, therefore, do not wish to restrict myself to the particular form of construction disclosed, but desire to avail myself of all modifications that may fall within the scope of the appended claims.

Having thus described my invention, what I claim and desire to obtain by Letters Patent, is:

1. In apparatus of the character described, a mica disintegrating unit comprising an elongated housing having a series of connected chambers for circulating pieces of mica in a liquid medium, said chambers being connected by restricted throats, the housing being provided with pairs of opposed lips defining said throats and one lip of each pair having a seat formed therein extending transversely of the housing, said unit being disposed so that the chambers are one above the other, and a liquid receiving tube rotationally adjustably fitted in each seat and having a line of perforations directed to throw a line of jets of said liquid across each throat and tangentially against the wall defining the chamber therebelow.

2. In apparatus of the character described, a mica disintegrating unit comprising an elongated housing having a series of connected chambers for circulating pieces of mica in a liquid medium, said chambers being connected by restricted throats, the housing being provided with pairs of opposed lips defining said throats and one lip of each pair having a seat formed therein extending transversely of the housing, said unit being disposed so that the chambers are one above the other, a liquid receiving tube rotationally adjustably fitted in each seat and having a line of perforations directed to throw a line of jets of said liquid across each throat and tangentially against the wall defining the chamber therebelow, said lines of jets constituting a barrier to circulation of the liquid in the unit from a lower to an upper chamber, said barrier creating a pressure in each lower chamber that displaces the

liquid therein downwardly, and a funnel connected at the bottom to the lowermost chamber and receptive of the liquid displaced from the chambers by the lines of jets.

5 3. In apparatus according to claim 2: the housing being provided on at least one side with a transparent closure plate affording visual inspection of the chambers and of the directions of the lines of jets, whereby control of the circulation of the mica pieces and the rotational adjustment of the tubes may be accurately effected.

4. In a mica disintegrating unit, a housing having at least two chambers arranged one above the other for circulating pieces of mica in a liquid medium, said housing having opposed lips defining a throat between said chambers, the lip on one side being provided with an open seat therealong, a perforated liquid receiving tube rotationally adjustably disposed in said seat and the perforations being directed toward the open side of the seat to direct a line of jets of liquid from the tube across the throat and tangentially against the wall of the lower of said chambers below the opposite lip, said line of jets constituting a barrier to flow of liquid from the lower to the upper chamber and the same inducing circulation of the liquid in the lower chamber and, consequently, circulation of the mica pieces therein, and a pair of perforated tubes on opposite sides 15 of the lower chamber and arranged parallel to the mentioned tubes, said latter tubes being rotationally adjustable to direct jets of liquid in a direction aiding the mentioned circulation of liquid and mica pieces in the lower chamber, 20 whereby the centrifugal force on the mica pieces resulting from the mentioned circulation, moves said pieces in a path adjacent to the wall of the lower chamber and, whereby said mica pieces assume a disposition substantially parallel to the 25 mentioned three jets as they move past said jets which, thereby, impinge on the trailing edges of the mica pieces to split them.

5. In a mica disintegrating unit according to claim 4: the housing being provided on one side 45 with a transparent closure plate affording visual inspection of the chambers and of the directions of the lines of jets, whereby control of the circulation of the mica pieces and the rotational adjustment of the tubes may be accurately effected.

6. In a mica disintegrating unit, a housing having a circulating chamber formed therein, said chamber having an open restricted top throat, a pair of inreaching lips defining said 55 throat, one of said lips having an open-sided seat formed therein along the length thereof, and a liquid-receiving tube rotationally adjustably fitted in said seat and having a line of perforations directed to throw a line of jets of said liquid across said throat and tangentially against 60 the wall of said chamber below the opposite lip.
